ELECTRICAL COUPLING SYSTEM

Application filed March 23, 1926. Serial No. 96,690.

This invention relates to translating circuits for high frequency currents and has as an object to provide a circuit having a uniform translating efficiency over a range of 5 frequencies.

It is a common practice to couple radio frequency circuits—such as the various stages of a vacuum tube amplifier—together inductively, that is, by the use of transformers or choke coils. As usually constructed such devices are objectionable for use in circuits adapted to operate over a range of frequencies, inasmuch as the reactance of the inductive devices increases with frequency.

15 In accordance with this invention the effects of the above objectionable characteristics of inductive coupling are reduced or eliminated by the use of a coupling transformer having two primary windings connected to the source of energy, together with means in circuit with the respective windings causing them to act differentially on a secondary winding at high frequencies, at which excessive transfer of energy would 20 normally occur, and causing them to act cumulatively on the secondary winding at the lower frequencies, at which insufficient energy would normally be transferred.

This application is a continuation in part 25 of my co-pending application, Serial No. 52,497, August 26, 1925.

Referring to the drawings:

Figure 1 is a circuit diagram showing the invention as applied to a high frequency 30 amplifier system.

Fig. 2 shows the characteristic curves of the reactance values of the coupling impedances.

Fig. 3 shows curves illustrating the effect 35 of increasing the decrement of the one impedance branch system.

Fig. 4 shows curves illustrating how the energy transfer ratio may be made substantially constant by this invention.

45 In Fig. 1 of the drawings this system has been shown as incorporated with a cascade amplifier comprising a plurality of amplifying devices such as electron emission tubes 10 and 11. These tubes are preferably of 50 the three element type and include a grid 12,

electron emission element 13 and plate or anode 14. Tube 10 is provided with an input circuit 15 and an output circuit 16 while tube 11 is provided with a similar input circuit 17 and output circuit 18. The input circuit 15 is coupled to a suitable source of signal energy of radio frequency and accordingly has been shown as provided with a secondary inductance 19 which is coupled to a primary inductance 20, 55 the inductance 20 being connected to an antenna 21 and ground 22. The input circuits 15 and 17 are connected across the grid and electron emission element of the respective tubes in the usual manner. The electron emission elements 13 are shown as energized by suitable A batteries 23 and 24 while the output circuits 16 and 18 are energized from a suitable source of current such as B batteries 26 and 27, the arrangement of these 60 A and B batteries being well known in the art. The output circuit 18 has been shown as connected to a translator, indicated diagrammatically at 28, such as a detector or further amplifying devices. 65

70 As a part of the means for coupling together the output and input circuits 16 and 17 respectively, the output circuit 16 is provided with at least two branch impedance paths 30 and 31 which are preferably reactive. The branch 30 includes an inductance L_2 , while the branch 31 includes an inductance L_1 and a capacitance C_1 . The input circuit 17 is preferably inductively coupled with at least one or it may be coupled with 75 both of the branches 30 and 31 as shown. Good results have been obtained by employing mutual inductive coupling comprising a secondary inductance coil 33 which is connected in series with the input circuit 17 and is positioned in inductive relationship with the inductances L_1 and L_2 , the inductance L_2 preferably being spaced farther from the inductance 33 than the inductance L_1 . The system is selectively tunable throughout a substantial range of radio frequency by suitable 80 means such as variable condensers 34 and 35 extending across the inductances 17 and 33 respectively. 85

100 The impedance branches 30 and 31 are pref-

erably selected so that their values of reactances correspond approximately to the characteristic curves shown in Fig. 2. In these curves abscissæ represent the frequencies of the selected energy, while ordinates represent reactances which may be either positive or negative according to whether they are above or below the horizontal axis. Thus if it is desired to design the coupling system for the present day broadcast range of from 200 to 550 meters corresponding to the vertical lines 32 and 36, the inductance L_2 is selected so that its reactance may be represented by the curve 2 which will be a straight inclined line above the horizontal axis as inductive reactance varies in direct proportion to frequency. The impedance branch 31 has the respective values of its inductive reactance L_1 and capacitative reactance C_1 proportioned so that the reactance of this branch will remain negative throughout the desired frequency range as represented by the curve 1. The values of the various reactances are also made such that the total reactance of the two branches 30 and 31 in series may be represented by the dash-dot curve 3 while the total reactance of the two branches in parallel, or that of the output circuit 16 may be represented by the dash-double-dot curve 4. The resonance frequency of the output circuit or the frequency at which the reactance of the two branches in parallel approaches infinity is represented by a vertical line 37 and is located just below the lower frequency limit of the frequency range. Thus, the resonance point has been shown as located at a frequency corresponding to 650 meters. The two branches 30 and 31 taken in series will be resonant at a point where their combined reactance is zero or the point at which the curve 3 intersects the zero reactance line. This point will also fall approximately upon the 650 meter line 37.

With the arrangement as described above, electrical energy of a given radio frequency in the output circuit 16 will divide between the two branch impedance paths 30 and 31 in accordance with the reactance values assumed by these branches. Since the reactance of the branch 31 is negative and that of the branch 30 positive, a circulatory current will be set up between the two branches, the magnitude of this circulatory current depending upon the relative reactances of the branches and therefore dependent upon the selected frequency. For the higher frequencies near the 200 meter limit the reactance of the branch 31 will have small negative values so that the circulatory current will be negligible and transfer of energy between the circuits 16 and 17 will occur through the differential effect of the inductances L_1 and L_2 upon the secondary inductance 33. It will be noted that the current in the output circuit 16 will produce opposed magnetic fields in

the coils L_1 and L_2 as the branch currents will flow in opposite directions. Therefore, for at least a portion of the frequency range currents can be induced in the input circuit 17 by the differential effects of the currents in inductances L_1 and L_2 . However, as the system is tuned for longer wave lengths or lower frequencies the transfer of energy will occur chiefly as the result of magnetic effects produced by the circulatory current which acts cumulatively upon the coils L_1 and L_2 to induce current in the secondary inductance 33.

Thus by properly selecting the reactance values the resultant magnetic field tending to induce current in the secondary coil 33 can be made to remain substantially constant and independent of frequency variations so that a constant proportion of the energy in the circuit 16 is always transferred to the circuit 17. Not only is this system useful from the standpoint of obtaining constant efficiency but it is also advantageous in case it is desired to operate the amplifier 10 regeneratively. Thus if a certain amount of energy is fed back to the input circuit 15 so that this tube operates regeneratively, then the reactance values of the impedance branches may be adjusted so that this regenerative condition is maintained throughout the frequency range without further adjustment.

The above arrangement gives approximately the results desired but the energy transfer ratio may be held to a closer constant by increasing the decrement of the output circuit 16. This is preferably accomplished by inserting a substantial resistance 40 in series with the impedance branch 30, such as a resistor of about 40 ohms. Fig. 3 shows the effect of this resistance upon the resonance of the output circuit. The dotted curve 5 illustrates how the resonance without the resistance 40 is relatively sharp or in other words the resistance rises suddenly to a maximum at the point of resonance. This peak is of course located beyond one limit of the desired frequency range, but it causes the percentage of energy transferred to be less for frequencies intermediate the limits of the frequency range than for frequencies near the limit thereof, as illustrated by the dotted curve 6 in Fig. 4. The effect of the resistance 40 is indicated by the curve 7 which shows that the decrement of the output circuit is increased, or in other words the resonance peak is made less abrupt. The effect of increasing the decrement of the output circuit is indicated by the curve 8 in Fig. 4 which is substantially a straight horizontal line showing that the intermediate frequencies are now transferred at substantially the same efficiency as the frequencies near the limits of the range. Another important function is served by the resistance 40 in that by adjusting the value of this resistance between

certain limits the circulatory currents in the branches 30 and 31 may be controlled for any one frequency without changing the natural period of the output circuit. This adjustment is very advantageous as it is proposed to employ a plurality of these coupling devices with a cascade amplifier and to operate the condensers 35 by means of a gang control. In such a system an individual coupling device may be adjusted by making variations in the resistance 40 without making a corresponding adjustment for an individual condenser 35. The capacitance C_1 is also preferably made adjustable or variable between certain limits so as to provide some means for effecting a variation in the relative reactances of the branches 30 and 31.

It is to be understood that the invention is not to be limited to impedance values which 20 will produce the various curves illustrated in the drawing. Various modifications of these values may be made without departing from the spirit of the invention as defined in the appended claims. The curves shown in 25 Fig. 4 are approximations for the purpose of illustrating the effect of the resistance 40.

I claim:

1. In a radio frequency amplifying system comprising amplifying means having input 30 and output circuits, means for coupling another circuit to said output circuit in a differential relation, said coupling means comprising inductances responsive to the amplified energy for controlling the proportional 35 amount of energy transferred at different frequencies, means for selectively tuning said coupling means, means connected in series with said selective tuning means for controlling the ratio of energy transfer for a 40 given frequency without affecting the tuning of the coupling means and connections from said output circuit to points intermediate said inductances and between said tuning means and said controlling means.

45 2. In a system of the class described comprising two electrical circuits, the first adapted to transfer oscillatory electrical energy to the second, at least two impedance branches in said first circuit, each branch including an inductance, a variable resistance in 50 series with one inductance, a variable capacity in series with the other inductance, means for inductively coupling said second circuit to both said inductances in a differential relation and connections for impressing variable potential at points intermediate said inductances and between said variable resistance and capacity.

60 3. In a system of the class described comprising two electrical circuits, the first adapted to transfer oscillatory electrical energy to the second, at least two impedance branches in said first circuit, each branch including an inductance coil, a resistance in series with one 65 coil and a condenser in series with another

coil, means for inductively coupling said second circuit to both said inductances, the fields induced by the current in said one circuit being opposed and means for impressing a high potential intermediate said coils and 70 between said resistance and condenser.

4. In a system of the class described comprising two electrical circuits, the second being adapted to receive oscillating energy from the first, at least two inductances electrically connected with the first circuit, a third inductance in the second circuit inductively coupled to the first two inductances, means for selectively tuning said system throughout a substantial frequency range, 80 and a resistance in series with said first two inductances for controlling the transfer of energy to said second circuit by their differential effect for at least a portion of said frequency range.

85 5. In a system of the class described comprising two electrical circuits, the second adapted to receive radio frequency energy over a substantial frequency range from the first circuit, a pair of reactive means included in the first circuit, one of said reactive means having a resonance period just beyond one of the limits of said frequency range, means for selectively damping said first circuit and means for coupling said second circuit to one of said pair of said reactive means.

90 6. In a system of the class described comprising two electrical circuits, the second adapted to receive radio energy over a substantial frequency range from the first circuit, reactive means included in the first circuit having a resonance period just beyond one of the limits of said frequency range, 100 means for coupling said second circuit to said reactive means, and means connected in series with said reactive means for varying the characteristic energy transfer curve for said range.

110 7. In a system of the class described comprising two electrical circuits, the second adapted to receive radio frequency energy from the first, at least two reactive impedance branches included in said first circuit, one of said branches including a resistance and an inductance, and the other of said branches including an inductance and a condenser, means for applying a potential to said first circuit across an intermediate point in said inductance and intermediate said resistance and said condenser and means for coupling said second circuit to at least one of said branches.

115 8. In a system of the class described comprising two electrical circuits, the second being adapted to receive energy from the first over a given frequency range, and means for electrically coupling said circuits together comprising at least two parallel reactive impedance branches in said first circuit, said

branches in parallel having a resonance period at a frequency located outside said frequency range, and means for increasing the decrement of said branches.

9. In a system of the class described comprising two electrical circuits, the second being adapted to receive oscillatory energy from the first over a given frequency range, and means for electrically coupling said circuits together comprising at least two parallel reactive impedance branches included in the first circuit, the relative values of said impedances being such that the resonance period for said first circuit lies outside but adjacent one limit of said range, and means for damping said first circuit.

10. A coupling system for effecting transfer of oscillatory energy between two circuits comprising two parallel reactive impedance branches included in one circuit, one of said branches including an inductance and a substantial variable resistance, and the other branch including an inductance and a capacitance, connections for impressing an exciting potential across an intermediate point in said inductance and between said variable resistance and capacitance and means for inductively coupling the other circuit to at least one of said branches.

11. A coupling system for effecting transfer of oscillatory energy between two circuits comprising two parallel reactive impedance branches included in one circuit, one of said branches including an inductance and a substantial variable resistance, and the other branch including an inductance and a capacitance, connections for introducing an exciting potential across an intermediate point of said inductances and a point between said variable resistance and capacitance and means for mutually inductively coupling the other circuit to at least one of said branches.

12. In a system of the class described comprising, energy amplifying means having control and output circuits, two branch reactive impedances in said output circuit, another circuit coupled to at least one of said branches, means for selectively tuning the system through a given frequency range, one of said impedances having a negative value of reactance for the lower limit of said frequency range, the natural period of both branches in series being below the lower frequency limit of said range and the natural period of said output circuit being above said frequency range, and means for substantially increasing the decrement of said output circuit.

13. In a radio frequency amplification circuit comprising a plurality of electron tubes a coupling system interlinking the output circuit of one tube with the input circuit of a succeeding tube, said coupling system including an inductance, a pair of branch circuits, one of said branch circuits including

a variable resistance and one portion of said inductance, the other of said branch circuits including a capacity and another portion of said inductance, the portions of said inductance and said branch circuit being differentially connected in said output circuit, an inductance disposed in the input circuit of said succeeding tube and coupled with said aforementioned inductance, said branch circuits being conjointly tuned to resonance at a wave length longer than the longest wave length to be received, and said branch circuit including inductance and capacity in series being tuned to resonance at a wave length shorter than the shortest wave length to be received for effecting a uniform transfer of energy over a predetermined wave length range.

14. In a system of the class described comprising two electrical circuits, the second being adapted to receive oscillatory radio energy from the first over a substantial frequency range, and means for electrically coupling said circuits comprising at least two parallel reactive impedance branches associated with the first circuit, one branch including an inductance and a substantial resistance, and the other branch including an inductance and a series capacitance, said inductances and capacitance being so proportioned that said two branches have two different points of resonance so that different degrees of coupling are provided for different frequencies within said range, said resistance serving to dampen the first circuit.

In testimony whereof, I have hereunto set my hand.

FREDERICK A. KOLSTER.
